(57) **CLAIM**

The ornamental design for a shoe, as shown and described.

DESCRIPTION

FIG. 1 is a side view of a shoe showing my new design;
 FIG. 2 is a front perspective view thereof;
 FIG. 3 is a rear perspective view thereof; and,
 FIG. 4 is a top view thereof.

The even-length broken lines are directed to environment,
 represent unclaimed subject matter, and form no part of the
 claimed design.

The long-and-short broken lines form an unclaimed bound-
 ary, and form no part of the claim.

1 Claim, 4 Drawing SheetsFIG. 1.

FIG. 2.

FIG. 3.

FIG. 4.
